UNITED STATES PATENT OFFICE.

WILLIAM WEBB AND WARNIE W. HILDRETH, OF GLOVERSVILLE, NEW YORK.

WRENCH.

No. 874,269.

Specification of Letters Patent.

Patented Dec. 17, 1907.

Application filed October 14, 1907. Serial No. 397,382.

To all whom it may concern:

Be it known that we, WILLIAM WEBB and 5
WARNIE W. HILDRETH, citizens of the
United States, residing at Gloversville, in the
county of Fulton and State of New York,
have invented certain new and useful Im-
provements in Wrenches; and we do hereby
declare the following to be a full, clear, and
exact description of the invention, such as
10 will enable others skilled in the art to which
it appertains to make and use the same,
reference being had to the accompanying
drawings, and to the letters and figures of
reference marked thereon, which form a part
15 of this specification.

This invention relates to certain new and
useful improvements in wrenches and more
particularly to the construction of pipe
wrenches and it has for its object the pro-
20 vision of a simple, inexpensive and efficient
tool of this character which is adapted to be
readily attached to a pipe and which will
automatically hold its position until the
wrench is used for turning the pipe.

25 The invention has for its further object
the provision in a wrench of this character of
a sliding or movable jaw integral with a slid-
ing member, the rear face of which is pro-
vided with a rack bar adapted to be engaged
30 by teeth formed upon the end of the handle,
the jaws of the wrench being held normally
closed by spring connection interposed be-
tween the head of the wrench and the jaw.

To these ends and to such others as the
35 invention may pertain, the same consists in
the novel features of construction and in
the peculiar arrangement, combination and
adaptation of parts, all as hereinafter more
fully described, shown in the accompanying
40 drawings and then specifically defined in the
appended claims.

The invention is illustrated in the accom-
panying drawings, which, with the letters of
reference marked thereon, form a part of
45 this specification and in which drawings:—

Figure 1 is a side elevation of a wrench
constructed in accordance with our invention,
the jaws of the wrench being shown as closed.
Fig. 2 is a top plan view. Fig. 3 is a side
50 elevation in section of the wrench with the
jaws shown as open, and Fig. 4 is an enlarged
perspective view of the sliding jaw detached.

Reference now being had to the details of
the drawings by letter, A designates the
55 handle of our wrench which is provided with
suitable gear teeth B, which are adapted to

engage the rack teeth C which are integral
with the laterally movable jaw D which is
adapted to move between the side walls E
of the pivotally mounted jaw F. One of the 60
side walls of the said pivotally mounted jaw
is provided with a laterally depressed recess
G adapted to engage a corresponding rib H
provided upon the inner face of the side wall
of the casing, this engagement of the rib 65
within the slide serving to insure direct lat-
eral movement of the movable jaw when the
wrench is operated by the movement of the
handle. The meeting faces of the fixed and
movable jaws are provided with the usual 70
serrations a to insure a firm grasp upon the
pipe or other article grasped between the
jaws. The handle is pivotally connected
with the head of the wrench between the side
walls of which it is disposed by means of a 75
suitable pivot I.

It will be noted that the shank or body
portion D', which is provided upon its rear
portion with the rack bar, the teeth of which are
adapted to be engaged by the teeth carried 80
at the end of the handle, is recessed to re-
ceive a rod, the lower end of which is con-
nected with the base plate J at the extreme
lower end of the head of the wrench and
around this rod is sleeved a coiled or spiral 85
spring K. When the movable jaw is opened
or moved outwardly by the action of the
handle, it will be noted that the outward
movement of the jaw will serve to depress
the spring, the tension of which is exerted 90
to normally hold the jaw against the face of
the fixed jaw or to hold the jaws in closed re-
lationship.

The fixed jaw F is provided with a mov-
able face plate G⁴, the rear face of which 95
plate is provided with an offset portion G⁵
which is adapted to be fitted within a corre-
sponding transverse recess G⁶ extending
across the fixed jaw and this movable plate
is held in position by means of a suitable 100
screw or bolt G⁷ passed through a screw thread-
ed opening in the jaw and plate.

From the foregoing description, the opera-
tion and advantages possessed by the wrench
will at once be understood. The lower jaw 105
being normally held with its face in contact
with the fixed jaw and being adapted to be
thrown out of such engagement only by
force being applied to the handle of the
wrench, it will be noted that, when a pipe or 110
other article is grasped between the jaws
of the wrench, the spring-actuated lower

jaw will be held normally in contact with the article grasped so that the wrench will be retained in operative position until the wrench is turned by the operator.

- 5 It will be noted that the wrench is of simple and inexpensive construction and adapted for all purposes for which wrenches of this character are designed. The advantage of the detachable face plate with the fixed jaw
10 will be at once evident as, when from use the serrations upon the face of the jaw become worn or dulled, the plate may be readily removed and the serrations sharpened or a new plate may be substituted therefor.

- 15 Having thus described our invention, what we claim to be new and desire to secure by Letters Patent is:—

1. A wrench comprising a fixed jaw having a shank made up of two walls spaced apart, a handle pivotally mounted between said walls and having rack teeth thereon, a sliding jaw having a shank movable between the walls to which said handle is pivoted and provided with rack teeth engaged by the teeth of said handle, the shank portion of the movable jaw being recessed, a plate connecting the ends of said walls, a spring positioned within the hollow shank of the slid-

ing jaw and bearing against said plate, serving to normally hold the jaws closed, as set forth.

2. A wrench comprising a fixed jaw having a shank made up of two walls spaced apart, a handle pivotally mounted between said walls and having rack teeth thereon, a 35 sliding jaw having a shank movable between the walls to which said handle is pivoted and provided with rack teeth engaged by the teeth of said handle, the shank portion of the movable jaw being recessed, a plate connecting the ends of said walls, a rod fixed to said plate and positioned within the recess of the shank of the sliding jaw, a spring mounted upon said rod and bearing at one end against the inner end of the shank of the sliding jaw 40 and its other end against said plate, as set forth.

In testimony whereof we hereunto affix our signatures in the presence of two witnesses.

WILLIAM WEBB.
WARNIE W. HILDRETH.
